Des. 210,437
Patented Mar. 5, 1968

210,437

HAIR DRYER OR SIMILAR ARTICLE

Melvin H. Boldt, Glenview, Ill., assignor to Schick
Electric Inc., Lancaster, Pa., a corporation of
Delaware

Filed May 18, 1967, Ser. No. 7,175

Term of patent 14 years

(Cl. D86—10)

FIG.1

FIG.2

FIG.3

FIG.4

FIG. 7

FIG. 8

FIG. 10

FIG. 9

FIG. 1 is a front view of my design for a hair dryer or similar article in the closed condition;

FIG. 2 is a side view thereof in the closed condition;

FIG. 3 is a top view thereof in the closed condition;

FIG. 4 is a bottom view thereof in the closed condition;

FIG. 5 is a side view thereof in the open condition;

FIG. 6 is a top view thereof in the open condition;

FIG. 7 is a view of the remaining side thereof in the open condition;

FIG. 8 is a bottom view thereof in the open condition;

FIG. 9 is a front view thereof in the open condition; and

FIG. 10 is a rear view thereof in the open condition; and

The dominant features of my design are disclosed in full lines on the drawing.

I claim:

The ornamental design for a hair dryer or similar article, substantially as shown.
